UNITED STATES PATENT OFFICE

GEORGE E. SMITH, OF BERKELEY, CALIFORNIA

SHOOTING GALLERY

Application filed May 21, 1928. Serial No. 279,286.

The present invention relates to an improvement in toy shooting galleries and has for its objects to provide a shooting gallery wherein the targets when struck fall to indicate the accuracy of aim; to provide a simple means for resetting the targets to their normal position after having been struck by a projectile emanating from the shooting element; to provide a means for varying the relative distance between the shooting element and the targets so that greater or less skill will be required on the part of the player to acquire accurate aim in striking the target, depending on the relative adjustment of the shooting element and targets.

With the above mentioned and other objects in view, the invention consists in the novel construction and combination of parts hereinafter described, illustrated in the accompanying drawings, and pointed out in the claim hereto appended; it being understood that various changes in the form, proportion, size and minor details of construction within the scope of the claim may be resorted to without departing from the spirit or sacrificing any of the advantages of the invention.

Reference is directed to the accompanying drawings, wherein—

Figure 1 is a view in side elevation of one embodiment of the invention, the device being in operative position.

Figure 2 is a view in front elevation of the hood, taken on line 2—2 of Fig. 1, showing the targets and target supports.

Figure 3 is a vertical sectional view of the hood, taken on line 3—3 of Fig. 2.

Figure 4 is a plan view showing the shape of the base board.

Figure 5 is a sectional view of the shooting element and means for mounting the same.

Figure 6 is an enlarged view, showing in detail the means of mounting one of the targets upon its target support.

In the drawings, wherein like characters of reference designate corresponding parts, the numeral 1 designates a base board having side walls 2 and 3, converging at their forward ends, as shown in Fig. 2 of the drawings, the base board being inclined toward the point

of convergence of said walls to enable the projectiles to roll forwardly. The board 1 is supported in the front and rear by legs 4, the former provided with an aperture 5 for telescopically receiving a bar 6. The outer or free end 7 of the bar 6 carries an upstanding base 8 on which is mounted a shooting element 9, as shown in Fig. 1. A hood 10 positioned with its opening normally facing the shooting element 9, is pivoted at 10' to the side walls 2 and 3, for movement from its normal position, full lines Fig. 1, to a horizontal target reset position, as shown in dotted lines, Fig. 1. Targets 12 are pivotally mounted on the supports 11, said supports 65 preferably disposed transversely across the interior of the hood and made integral therewith by being attached to the side walls thereof.

Each target is provided with an apertured bracket 13 extending at right angles from the rear thereof, each being connected through pins 15 with an apertured ear 14 extending from the target support 11, they allowing the target to fall backwards from its vertical position, Fig. 6, when struck by a projectile from the shooting element 9. The face of each target may be ornamented with any suitable character outline or picture, as illustrated in Fig. 2. Forwardly from each target at right angles to its face extends a counterbalancing plate 17, designed to maintain the target upwardly disposed when in its set position, the plate on its underside carrying indications of value to be given to the target when the same is struck and upset to the dotted line position, Fig. 6.

The barrel of the shooting element 9 extends through base 8, and is universally fulcrumed therein through a ball and socket joint 16. A spring 16' positioned within the base 8 bears against the follower 16² for maintaining a uniform tension on the barrel 18 of the pistol 9.

The pistol is provided with a projectile receiving magazine 19 positioned above and extending parallel with the rear of the barrel. The magazine and barrel, for a portion of their length, are respectively longitudinally slotted as at 19' and 20, and the magazine 19

is further provided with a filling aperture 27 extending through its upper wall, near its rear end, for receiving the projectiles 28. The magazine 19 is provided with a spring follower 21, carrying a pin 23 extending through the slot 19'. The barrel 18 is provided with a spring actuated projectile-ejecting plunger 24 carrying a plunger cocking pin 25 extending through the slot 20.

10 In operation, the follower 21 is moved rearwardly in the magazine by operation of pin 23 until its forward end lies rearwardly of the aperture 27, at which time projectiles 28, of substantially spherical form, are inserted 15 therein, the follower 21 advancing the same within the chamber on each successive firing of the apparatus. The plunger 24 is moved rearwardly to cocked position with its forward end rearwardly of the port 29, affording 20 a connection between the magazine and the barrel, enabling the foremost projectile in the magazine to drop into the barrel. The lip 30' of trigger 30, actuated by the spring 31, releasably engages the forward end of 25 plunger 24 in cocked position. The projectile lying in advance of the cocked plunger 24 rests in the depression 32, in the trigger surface, and is thus precluded from rolling longitudinally of the barrel. The resetting 30 of the targets to their operative position is accomplished by tilting the hood forwardly on its pivots 10' to dotted line position, Fig. 1, after which the hood is returned to its normal operative position. The fired projectiles 35 drop onto the inclined base board and roll forwardly into a depression 34 formed at the point of convergence of the walls 2 and 3.

It will be seen that by varying the relative 40 distance between the shooting element 9 and the targets, greater or less skill will be required on the part of the player to make a direct hit upon the targets.

I claim:

45 A game apparatus comprising a hood having an open front, side walls and a curved back wall, a base to which said hood is freely pivoted on its opposite sides on a horizontal axis, said base provided with a bottom wall 50 inclined forwardly from said open front, a shooting element carried in advance of the hood, a plurality of transversely disposed target supports mounted within the hood and attached thereto, said supports adapted to 55 move with said hood, a plurality of targets within said hood, each mounted to pivot on a horizontal axis parallel with the axis of the pivot of said hood, a counterweight associated with each target for normally maintaining 60 the same in upright position, said target counterweights adapted for assuming a substantially vertical position on the tripping of the target to a substantially horizontal position by the contact of a projectile discharged 65 by said shooting element therewith, said tar-

gets adapted for simultaneous resetting on the pivotal movement forwardly of said hood and its return to normal position.

In testimony whereof I have signed my name to this specification.

GEORGE E. SMITH.
